UNITED STATES PATENT OFFICE.

PHILIP B. WALLACE, OF SAN FRANCISCO, CALIFORNIA, ASSIGNOR TO CHADWICK & SYKES, INC., OF SAN FRANCISCO, CALIFORNIA, A CORPORATION OF CALIFORNIA.

COMBINED ROPEWAY.

1,197,083.

Specification of Letters Patent. Patented Sept. 5, 1916.

Application filed March 3, 1915. Serial No. 11,710.

To all whom it may concern:

Be it known that I, PHILIP B. WALLACE, a citizen of the United States, residing at the city of San Francisco, in the county of San Francisco and State of California, have invented certain new and useful Improvements in Combined Ropeways, of which the following is a specification.

My invention relates to improvements in 10 ropeways.

The object of my invention is to provide a ropeway having an improved carrier supporting a container for containing the load whereby the same is dumped with certainty 15 and expeditiously on contact with a suitable bumper.

My invention consists in the combination and arrangement of parts shown in the accompanying drawings, described in the following specification, and claimed in the appended claims.

Referring to said drawings, Figure 1 is a side view of the carrier and bucket employed in the apparatus; Fig. 2 is an edge view of 25 said carrier; Fig. 3 is a view similar to that shown in Fig. 1, but showing the bucket in the dumping position, and Fig. 4 is an end view of the bumper employed in said apparatus.

30 In said figures 2 represents a cable. Carrier 6 is supported on cable 2 by sheaves 9 mounted thereon and has depending therefrom block 13 from which is supported by chains dumping bucket 16, said bucket being secured on one end thereof by chains 15^b, while the other end thereof is held by chain 15^a detachably supported by finger 17 pivoted to block 13. A tripping bumper 44 is attached for the operation to cable 2 at the 35 point where the dumping of the bucket or container 16 is desired. The carrier 6 on cable 2 to convey the material to the dumping point is actuated by gravity when released by a suitable holding device until the 40 carrier arrives at the tripping bumper 44, when the load of material in said bucket is dumped by contact of the container therewith. The dumping of bucket 16 attached by back chains 15^b and front chains 15^a to 45 carrier block 13 is effected by the breaking of the toggle 18 by the striking of said toggle near its center by the lug 49 of bumper 44, which bumper 44 is attached to

cable 2 for the operation at the point where the dumping of bucket or container 16 is desired. The striking of the toggle 18 is done by the movement of carrier 6, from which block 13 is suspended on the cable 2, toward bumper 44 till contact between said lug 49 and the toggle occurs. The breaking of 55 said toggle causes the raising of forked arm 41 connected by pivot 42 to block 13 as a center of rotation and permits the finger 17 engaging roller 45 secured in the apex of the forks of forked arm 41 to fall by rotation 60 on the pivot 46 and thereby releasing the upper ring 52 of the front chain 15^a as secured at 53, and permitting the fall of one end of the bucket 16 as held by said front chain and the consequent emptying of the 70 bucket.

In my improved carrier for ropeways I prefer to employ rollers 9 upwardly pivoted thereto so that the same may travel on cable 2; and cable 10 is secured to said carrier by bolt 14, then passes downwardly under sheave 12 pivoted to block 13, then passes upwardly over sheave 11 pivoted to 75 said carrier toward a suitable drum for winding the same so that the block can be 80 lowered from the carrier when pin 24 is released by pivoted latch 23, which is held up by means of a roller 22 pivoted to the releasing hook 19. By the pulling of said hook on pin 20 in slot 21 of said carrier the latch 85 23 may be released from said roller 22. Hook 19 has notches as shown for holding the same, including notch 25.

The bumper 44 may be secured to the cable 2 by a screw or other suitable means so 90 that the same may be moved to any position on the cable 2 below which it is desired to empty the container 16.

The hook 19 for holding the carrier is provided with a pin 20 centrally secured 95 therein and slidable within the slot 21 of the plates or side walls of the carrier 6. The carrier has bar 50 for engaging the notches shown in proximity thereto. The pin 20 being secured to and forming part of bar or 100 hook 19, shown in dotted lines, may be moved to the right in slots 21 in the walls of carrier 6 so as to release roller 22 from latch 23, thereby permitting the lowering of the fall block shown. The bar 19 has an 105 inclined surface 51 for engaging a suitable

holding device. The contact of carrier 6 with bumper 44 forces bar 19 to the right as shown in Fig. 3.

I claim:

- 5 1. In combination with a track, a carrier thereon having a member suspended therefrom, a support pivoted to said member and having a free end, a container having one end connected to said member and the other end provided with a chain engageable by said support, a bar pivoted to one end of said member and having a lateral projection engageable with the free end of said support and a toggle secured to said member and pivoted to said bar for the movement of said bar.
- 10 2. In combination with a track and a bumper connected to said track and provided at its lower end with a lug, a carrier

on said track having a member suspended 20 therefrom, a support pivoted to said member and having a free end, a container having one end connected to said member and the other end provided with a chain engageable by said support, a bar pivoted to one 25 end of said member and having a lateral projection engageable with the free end of said support and a toggle secured to said member and pivoted to said bar for the movement of said bar upon the engagement 30 of said toggle with said lug.

In testimony whereof I affix my signature in presence of two witnesses.

PHILIP B. WALLACE.
